CONVERTIBLE WARDROBE HANDBAG

Herbert B. Marbury and Roy C. Jones, Atlanta,
Ga., assignors to Fulton Bag and Cotton Mills,
Atlanta, Ga.

Application March 6, 1937, Serial No. 129,481

2 Claims. (Cl. 190—43)

Generically this invention relates to clothes containers, but it more especially is directed to a combination wardrobe travelbag and handbag, and constitutes an improvement of the subject 5 matter of our applications, Ser. No. 25,165, filed June 5, 1936, Ser. No. 61,408, filed January 20, 1936, now issued as Patents Nos. 2,087,210 and 2,087,211, respectively, and Ser. No. 85,993, filed June 18, 1936.

One of the principal objects of this invention is the provision of a combination wardrobe travel and handbag formed at its front surface with a cut-out opening of such dimensions and disposed at such an angle as to permit the expeditious insertion and removal of the contents of the bag, said cut-out portion constituting a closure flap for said opening, and fastener means for securing the flap in closed position.

An important object of this invention is the 20 provision of a substantially flat flexible sack-like container adapted to normally support therein clothes and the like in wardrobe fashion when in extended position, and adapted to be folded and secured in folded position to provide a thin brief-case like handbag.

One of the important objects of this invention is the provision of a combination wardrobe, travel and handbag or container of this character having supporting means for suits of clothes or the like, and a cut-out portion in the front surface constituting a closure flap and fastening means therefor permitting ready access to said clothes, an exterior compartment adjacent the upper end of the container suitable for holding shirts, pajamas, and other articles of clothing, etc., having a slide fastener controlled opening preferably extending longitudinally of the compartment adjacent its upper edge, an opening preferably vertically formed in the inner wall of said compartment and the rear wall of said container spaced from one end of the compartment and edge of the container having suitable fastening means permitting access to the compartment from the interior of the container, said rear longitudinal opening adapted to permit ready access to the compartment without interfering with the first mentioned or primary container opening and irrespective of whether the container is in extended or folded position, said outside compartment adapted to provide means for carrying wearing apparel and toilet accessories without such articles pressing against or wrinkling the suits or dresses carried within the container and, thereby, also providing additional space inside 55 the container for suits, dresses, and the like.

Another object of the invention is the provision of a combination container of this character provided with compartments exterior of the rear wall of the container having slide fastener controlled openings whereby access may be had to said compartments irrespective of whether the container is in folded or extended position, and so arranged that when the container is in handbag or folded position the containers are balanced with respect thereto and constitute in effect opposite exterior 10 surfaces of the handbag, said compartments being so constructed as to effect an increased carrying capacity without affecting, by wrinkling or otherwise, the contents of the container and without materially altering its brief case-like effect or changing its flexibility, and at the same 15 time yet adapted to maintain in upright position the handbag when the same is set on the floor or other supporting surface.

Another important object of this invention is 20 the provision of a combination wardrobe, travel and handbag or container of this character and in addition to the outside compartment above referred to, formed with an exterior compartment for shoes, toilet articles, etc. and having a 25 slide fastener controlled opening, so that ready access may be had thereto irrespective of whether the container is in extended or folded position, and when folded said container is adapted to constitute a substantially thin brief case-like 30 handbag.

A further important object of this invention is the provision of a combination wardrobe, travel and handbag or container of this character having an improved hanger structure including a 35 swivel or link connection between the hanger body and its supporting hook, so that said hook may be engaged in its supporting ring without tilting the hanger with the clothes, and permitting the insertion or selective removal of different articles of clothing without difficulty, and an opening formed in the front surface of such dimensions and disposed at such angle as to permit ready access to the interior of the container and the clothes carried by said hangers, said cut-out portion constituting a closure flap for said 40 opening and having fastening means, and rack means carried by the inner surface of said flap adapted to carry neckties and the like and prevent wrinkling thereof during the handling of the 45 container.

Another principal object of this invention is the provision of a flexible travelbag, adapted to support therein clothes in wardrobe fashion and to be normally suspended in extended position 55

when traveling by automobile, train, bus, plane, or steamer, and instantly convertible into a handbag by simply folding the bag upon itself with its free end detachably secured to one side there-
5 of, and having a strengthening attaching adjustable strap means secured to the upper end of the container and having detachable connection with its opposite end to supportingly maintain the folded section in position, said means additionally
10 adapted for detachable supporting connection with a ring, hook, nail, pole, or other anchor element attached to a supporting medium.

A further important object of this invention is the provision of a combination travel bag and
15 handbag constructed from a one or two-piece blank adapted to normally support therein clothes in wardrobe fashion when in extended position, so constructed as to eliminate interior obstructions tending to wrinkle the clothes when
20 folded to provide a handbag, said bag being airtight when closed whether in extended or folded positions, and constituting a permanent moth and dust repellent sealed clothes container when not being used for traveling purposes, said container adapted to maintain the clothes in non-wrinkled condition, and instantly available as a travel and handbag when desired.

With these and other objects in view, which will become apparent as the description proceeds,
30 the invention resides in the construction, combination and arrangement of parts, hereinafter more fully described and claimed, and illustrated in the accompanying drawings, in which like characters of reference indicate like parts throughout the several figures, of which:

Fig. 1 is a front elevation of our improved convertible handbag in open position.

Fig. 2 is a vertical cross sectional view taken on the line 2—2 of Fig. 1.

Fig. 3 is a horizontal section taken on the line 3—3 of Fig. 1, but with the front flap closed.

Fig. 4 is a rear elevation of the handbag or container, showing the exterior compartments and the fastening means for both compartments in closed position.

Fig. 5 is a vertical section showing the front flap closed and the upper compartment open.

Fig. 6 is a perspective view of the device folded to constitute a handbag.

Fig. 7 is a fragmentary detail sectional view taken on the line 7—7 of Fig. 4.

The types of luggage cases or handbags with which we are familiar have proven deficient in many ways, such as being too bulky, too expensive to produce, having foldover flaps, interior compartments, etc., causing wrinkling of the clothes when folded, incapable of use as a handbag and also as a wardrobe container when traveling and as a clothes container when not in use for traveling, and it was to overcome such deficiencies and to provide a substantially flat, flexible, airtight, waterproof, dustproof, moth-proof wardrobe container while being transported by land, air, or water, having auxiliary exterior compartments mounted on the rear wall of said container and effecting a balanced arrangement and in effect supporting base when the container is folded as a handbag and expeditiously independently accessible irrespective of whether the container is in folded or extended position, one of said compartments being additionally accessible from the interior of the container so that filling of the compartments will not affect the interior capacity of the container and in addition prevent wrinkling or massing of the contents of the

container when the latter is in folded position, that we designed the combination travel and handbag forming the subject matter of this invention.

In the illustrated embodiment characterizing this invention there is shown a travelbag A in which principally clothes are adapted to be normally carried wardrobe fashion. The luggage case or travelbag A is formed from a one or two-piece substantially rectangular blank of flexible material such as suede, leather, canvas, or other suitable material transversely folded upon itself by bringing end 1 upwardly thereover and with its side edges and curved end edges turned inwardly in overlapping relation and stitched with 15 a liner strip or insert 2 interposed therebetween and extending to the exterior so as to form a water and airtight seam and enhance the appearance of the bag. If it is desired to use a two-piece blank and the bag is similarly formed except that the inwardly turned edges will be stitched all the way around.

In order to provide an opening B of proper size, yet so designed as to permit complete access to the interior of the bag and the expeditious insertion therein and removal therefrom of clothes and other articles, the front side or face 3 is cut forming a slot 3' substantially conforming to the contour of said upper edge from a point 4 spaced from one side edge and from the upper edge transversely to a point 5 spaced from the opposite side edge and downwardly to 6, thereby forming a substantially triangular flap 7, having a hingelike fold line 8 extending diagonally from the starting point 4 of said cut to the end 6.

In order to lock and hold the flap 7 in closed position, a tape (a) is secured by stitching (b) to the under surface of side 3 along the edge of the opening B and a similar tape (a) similarly secured along the periphery of the flap with their meeting edges extending substantially to the center of the slot when the flap is in closed position. Suitably cooperating fastening means 9 may be applied to the meeting edges of the respective tapes, comprising the well known form of interlocking metallic eyes or loops 10 which are moved into and out of interlocking engagement by means of a slide 11 provided with an operating tab 12. By drawing the slide 11 in one direction, the elements of the fastener are interlocked and the flap is moved to and held in closed sealed position. By drawing or pulling the slide in the opposite direction, the elements of the fastening means are disengaged causing the flap to automatically move to open position. It is therefore apparent that the movement of slide 11 not only fastens and unfastens the flap but at the same time effects, without other aid, movement of the flap from complete open to complete closed position, as desired. In this connection, it will be noted that the metallic elements 10 of fastening means 9 when in interlocking or bag sealing relation are positioned in slot 3' and below the exterior surface of the bag.

A tab (c), in the present instance, substantially shield-shaped is suitably secured to the bag at the ends 4 and 6, respectively, of slot 3' as a reinforcement and protection to the ends, respectively, of the slot and hinge fold 8 of said flap, which are also adapted to add to the appearance of the bag.

The ends 13 of handle 14 are interposed between and extend beyond the upper meeting

edges of the sack or bag A and are secured by the stitching 1' uniting the said edges. While in the present instance the bag and handle are shown as preferably constructed of waterproof suede, either or both may be constructed of any suitable material. Each of said ends 13 of handle 14 is divided and tacked or otherwise suitably secured to opposite sides of a hanger support 15 constructed of wood or any suitable material of a length substantially equal to the interior width of the sack and curved to conform substantially to the contour of its upper end, so that the weight of the bag will be distributed over said upper end.

Support 15 not only effects an even distribution of the weight of the sack over its upper end, but maintains the shape of the sack or bag at all times and additionally constitutes a supporting medium for articles of clothing placed on one or more of the clothes hangers 16 detachably supported by the anchor screw 17 threadedly or otherwise secured to said support 15. The hook portion (d) of the respective hangers 16 is connected by the link or swivel connection (e) to the body of the hanger, so that when a suit of clothes or other articles of clothing are supported on said hanger 16, the hanger will not have to be tilted in order to engage hook (d) with anchor screw 17, which owing to space is an important item, such connection also permits free movement of said hangers so that different articles of clothing may be selectively and easily removed and replaced in the container.

A rectangular piece of flexible material 18 preferably similar to that from which the container proper is constructed, is imposed on the exterior side 20 adjacent its upper end, with its upper edge interposed with liner strip 2 between the meeting ends of sides 3 and 20 and united by stitching 1' as heretofore described. Said strip 18 is folded at a point spaced from its lower longitudinal edge substantially at right angles thereto, forming portion 21 and then inwardly overlying side 20 to which it is secured by stitching 22, thus forming in cross section an elongated triangular expandable compartment F. The ends of said compartment are closed by the similarly shaped end pieces 21' having their surrounding edges secured to piece 18 and between the meeting edges of sides 3 and 20 with an interposed liner strip 2 by stitching 1' as will be clear without further discussion.

The portion 21 is adapted to increase the content capacity of said compartment and also to constitute a supporting foot-like element adapted to maintain (in conjunction with a similarly oppositely positioned element directly to be described) the handbag in an upright position when placed on the floor or other supporting medium, as will hereinafter more fully appear. Said compartment is formed in its inner wall, which is also the inner wall of said container, with a vertical opening 23 spaced inwardly from one edge of the container and the end of the compartment and having secured therein a closure and fastening structure similar to that described in connection with opening B, namely, (a) (b), 9, 10, 11 and 12.

It has been found that while an inner compartment mounted on the inner rear wall of the container for holding shirts and other articles is efficient so far as maintaining such articles in unwrinkled condition, etc., yet it has been found deficient in that when such compartment is filled it takes up space within the container, thereby

decreasing the content carrying capacity of the main container and interferes with such contents when the container is in folded position, and therefore it has been found advantageous to substitute therefor compartment F mounted exteriorly of the container, so that the filling of said compartment does not affect in any way the interior space or contents of the container. It has also been found of advantage to provide opening 23 by means of which access may be had to the compartment through opening B and from within the container, substituting said opening for the open end of the compartment as heretofore practiced. It will thus be seen that this compartment is entirely separated from the interior of the container and access may be had thereto from either the outside or inside of the container as desired.

Two or more sectional fastening elements 24, in the present instance of the well known snap fastener type, are suitably secured to side 3 in spaced relation intermediate the upper edge of the L-shaped opening B and the upper end of the container, each being correspondingly spaced from said upper end of the container. The complementary sections 25 are suitably secured to the lower edge of bag A and correspondingly curved to said upper edge, so that when it is desired to convert the wardrobe travel bag A into a handbag C, it is only necessary to transversely fold said bag upon itself as at 26 and bring the elements 24 and 25 into interlocking engagement. It will be noted that this arrangement not only makes a uniform and pleasing appearance, and entirely conceals the opening B, but effects a stronger connection by having the anchor elements 24 secured to the upper portion of side 3 adjacent to and supported by the support 16, and which also takes all strain off of the fastening means 9, when being carried as a handbag.

In order to strengthen the fastening means and prevent any tendency of the folded over portion to sag or the fastener elements 24 and 25 to separate when the bag, and especially compartment E (hereinafter to be described) is heavily loaded, we have provided what may be termed an auxiliary strap fastening and supporting element 36, having one end secured between the inwardly folded edges of sides 3 and 20 by stitching 1' and tacked or otherwise attached to one side of the support bar 15. A short loop strap 37 carrying buckle 38 is also secured between the inwardly folded edges of sides 3 and 20 superimposed on strap 36 and with its end tacked or otherwise attached to the side of bar 15 opposite to the attached end of strap 36. A loop strap 37' carrying ring 38' is secured between the inwardly folded edges of sides 3 and 20 at the bottom edge of the container, and when the container is folded and strap 36 is brought through said ring and secured by buckle 38 said strap will maintain the bag in folded position and especially render it easier to effect engagement of the fastener elements 24 and 25 at each corner of the folded end of the bag. This construction will also not only tend to transfer much of the weight directly to the support 15 but center the pull with respect to the handle 14, thereby effecting in conjunction with fastening elements 24 and 25 a better balancing of the load lengthwise of support 15, and transversely thereof by the addition of compartment F opposite to compartment E. It will be observed that this strap arrangement is designed to serve a double purpose, first as a means for supporting the lower or folded section when the container is folded as a handbag, and, secondly, when the container is in ex-

tended position, it is adapted to be passed around the rod in a Pullman berth, the rod in a clothes closet, the rod back of the front seat of an automobile, or over a hook or through a ring. The 5 handbag may be reconverted into the wardrobe bag by simply disengaging the fastening elements 24 and 25 and buckle 38 from strap 36. In this connection it will be noted that only one handle 14 is employed, the same being common to both 10 forms A and C.

Access as above described may be had to compartment F through openings B and 23, when the bag is suspended by handle 14, but as this can only be done when the bag is in extended 15 position, and since it is often necessary to gain access to said compartment for the purpose of removing handkerchiefs and the like, it has been found expedient and desirable to provide means for gaining access to said compartment without 20 having to disturb any of the contents of the container and without having to first unfold the container, and which we accomplished by forming a slot or cut-out portion 27 in the back or rear side 18 of said compartment, and having 25 secured therein, a closure and fastening structure similar to that described in connection with opening B, namely, (a), (b), 9, 10, 11 and 12.

A necktie or scarf rack structure D comprising the spaced loop or strap members 28 and 29, secured by brads 30 or other suitable fastening 30 means, are mounted on the inner surface of flap 7.

Compartment E is similar to compartment F except that it is oppositely positioned, that is, 35 a piece of material 31, similar to 18, is mounted on side 20 adjacent the end of the container opposite to handle 14, with one edge interposed between the meeting ends of sides 3 and 20 and united by stitching 1'. Said piece 31 is folded 40 at a point spaced from its remaining longitudinal edge substantially at right angles, thereby forming portion 32, similar to portion 21, and then inwardly as at 33 overlying side 20 to which it is secured by stitching 34, thus forming said 45 compartment E, similar to compartment F, and with similarly formed and secured end pieces 21'. It will be apparent that the supporting foot-like portions 21 and 32 support the folded container or handbag in upright position when 50 placed on a supporting surface, notwithstanding their flexible and foldable nature, permitting, if desired, collapsing of said compartments when not in use.

The compartment E, like compartment F, exterior of the bag, has been found necessary to 55 preclude the possibility of wrinkling of the wearing apparel inside of the bag, since shoes and other contents adapted to be carried by this compartment cause wrinkling of such apparel, 60 and even if it were on the inside of the bag, such shoes and other contents would press against the garments and tend to wrinkle them, thereby defeating one of the primary purposes of the bag, which is to carry suits, dresses and other apparel 65 without their being wrinkled.

In order that ready access may be had to said compartment E, it is formed, preferably adjacent its upper edge when the container is folded as a handbag, with a longitudinal slot or cut out 70 portion 35 and a fastener closure means therefor, similar to that described in connection with opening 27 in compartment F, namely, (a), (b), 9, 10, 11 and 12.

It will be observed that the compartments E 75 and F, somewhat triangular in cross section, are

designed to present increased capacities and so arranged with respect to each other as to overcome certain disadvantages of previous container construction, adapted to effect a balanced handbag structure, without affecting the contents or foldability of the container, and additionally adapted to supportingly maintain the handbag in upright position when placed on the floor or other surface, without detracting from or affecting the flexibility of the container. 10

With further reference to the insertion of articles of clothing such as suits and the like in the container and their removal therefrom, it might be further stated that the L-shaped cut 3' forms the opening B, ordinarily referred to 15 as the L opening, and which particular type of opening has been found to greatly facilitate the insertion of the clothes in the bag and their removal therefrom, and in addition forms the upper overhanging portion of side 3 suspended 20 from the supporting member 15, and which is adapted to support the folded over portion of the container with its exterior compartment. This manner of supporting and detachably securing the container in folded position not only 25 prevents strain on and distortion of the L-shaped fastening means, but completely hides said means from view, thereby enhancing the appearance of the bag when folded as a brief case-like handbag. 30

Again, the wardrobe, travel and handbag, constructed in accordance with this invention, when being carried as a handbag or suspended from a supporting element in a stateroom, Pullman car, airplane or automobile, ready access may be 35 had to compartments E and F without unfolding the handbag, and when in extended position access may be had to the container and compartment F from one side and to the interior of the container and both compartments without 40 removing the container from its supporting element.

The operation and versatility of our improved light weight, compact, combined travel bag and handbag would seem to be clear from the above 45 description.

From the above it is apparent that we have designed a unique combined wardrobe bag and handbag, manufacturable at a minimum of cost, adapted if desired to be supported in extended 50 position when being transported by automobile, train, bus, plane or steamer, affording a compact way of carrying suits and other articles without wrinkling, etc., eliminating troublesome packing and unpacking, providing a light, conveniently 55 handled protection for said suits, the latter being instantly available by simply moving the slide fastener member to complete flap opening position, or only sufficiently to partially open said flap if other articles such as shirts are desired; 60 and from this point to reconvert the wardrobe bag, simply close the slide fastener, transversely fold the bag, snap the complementary fastening elements into interlocking engagement and/or fasten said strap means, and a compact handbag 65 is the result.

Further, if it is desired to gain access to the auxiliary compartment F without interfering with suits, dresses, or other articles carried by the container and without opening said flap closure 70 7, it is only necessary to move in opening direction the slide fastener normally closing opening 27, whereby access is had to said auxiliary compartment F for the insertion or removal of shirts, socks, handkerchiefs, underwear, or other 75

wearing apparel, and similarly, with respect to the slide fastener normally closing opening 35 in compartment E and irrespective of whether the container is in extended or folded position.

5 Although in practice we have found that the form of our invention illustrated in the accompanying drawings and referred to in the above description, as the preferred embodiment, to be the most efficient and practical; yet, realizing the 10 conditions concurrent with the adoption of our invention will necessarily vary, we desire to emphasize that various minor changes in detail of construction, proportion and arrangement of parts, may be resorted to within the scope of the 15 appended claims without departing from or sacrificing any of the principles of this invention.

Having thus described our invention, what we desire protected by Letters Patent is as set forth in the following claims:

20 1. A foldable travel bag including parallel flexible side members united at their edges to form a sack, means in connection with one of the side members to afford access to the interior of the sack, a pair of compartments attached to 25 the other side member, said compartments including adjacent bottom portions extending outwardly from said other side member in parallelism from opposite sides of the fold line of said side forming a central portion, front portions integral 30 with the bottom portions tapering upwardly therefrom to opposite ends of the sack producing in effect a Gladstone configuration, whereby when

said sack is folded said bottom portions form a continuation of the central portion of said other side member and constitute therewith an extended base, means in connection with the respective compartments to afford access to their interiors, and means for detachably securing the bag in folded position. 5

2. A wardrobe travel bag foldable into a container comprising a sack having flexible parallel side walls, an opening in one side wall to 10 afford access to the interior of the sack and having suitable closure means, said container being adapted to be folded substantially central of its length into a hand bag, a pair of exterior compartments mounted on the rear wall of said container on opposite sides of said fold line and having parallel widened opposed bottom portions adapted to form a central base portion, said bottom portions in conjunction with said central base portion constituting an extended base when 15 said bag is folded into a hand bag, said compartments having normally closed exterior openings, one of said compartments having an additional normally closed opening in its rear wall and that of the sack spaced laterally from the side edge of 20 the sack and the vertical edge of the sack opening, whereby access may be had to the last mentioned compartment both exteriorly and interiorly 25 of the sack.

HERBERT B. MARBURY. 30
ROY C. JONES.
